CONTROLLING MEANS FOR REFRIGERATING APPARATUS

John Kirgan, Easton, Pa., and George H. Woodward, Phillipsburg, N. J., assignors to Ingersoll-Rand Company, Jersey City, N. J., a corporation of New Jersey

Application October 24, 1934, Serial No. 749,704

12 Claims. (Cl. 62—152)

This invention relates to refrigerating apparatus, and particularly to controlling means for a refrigerating system in which the necessary effect is obtained by cooling and circulating a suitable refrigerating medium.

The invention is particularly designed for use in connection with a refrigerating system comprising a vessel in which a liquid refrigerant, such as water, is chilled, and from which it is conducted to the place where the refrigerating effect is to be produced. In installations of this kind, the refrigerant is often transmitted to a considerably higher level than the vessel or evaporator in which the temperature of the refrigerant is diminished, so that the water or other liquid refrigerant, as it flows back to the evaporator to be again chilled, travels from a higher point to a lower one. Proper control of the returning water to enable the output to be reduced as working conditions require, or to prevent flooding of the evaporator, when the operation of such a system is stopped or in the event of a mishap, or for other purposes, is therefore desirable.

The principal object of this invention is to provide a simple and efficient controlling arrangement for refrigerating apparatus of this kind.

A further object of the invention is to provide refrigerating apparatus having means in the form of one or more valves, disposed to be actuated and released through the instrumentality of the refrigerant itself, to facilitate controlling the system in the manner above stated.

Other objects and the nature and advantages of the invention are fully described hereinafter, and several constructions in which the invention is embodied are illustrated in the accompanying drawings. The disclosure, however, is by way of explanation only, and we may make changes in the shape, size and arrangement of the various parts without going beyond the principle of the invention or exceeding the spirit and scope of the claims appended hereto.

On the drawings, Figure 1 shows one embodiment of the invention, and

Figure 2 shows a modification.

With reference to Figure 1, in which some of the parts appear in vertical section, the numeral 1 indicates a vessel called an evaporator to which water is supplied by a pipe 2. This pipe has inlet branches 3 and 4 entering chambers 5 and 6 respectively in the evaporator 1. In each of these chambers the water is discharged through an inlet header 7 having a number of openings 55 to enable the water to issue in the form of a spray.

By suitable evacuator devices (not shown) the pressure in the evaporator chambers 5 and 6 is greatly reduced, so that the water, which enters at a given temperature, is partly vaporized. The vapor thus formed is removed from the evaporator by the said evacuator and carried into a condenser (not shown) to be liquefied. The process of vaporization extracts some of the heat from the remaining water and thus the temperature of the main body of the water is decreased. 5 The chilled water at the bottom of the chambers 5 and 6 is delivered to a pipe 8 connected to the chambers 5 and 6 through branches 9, and through the pipe 8 the chilled water flows to the place where refrigeration is to be accomplished. 10

In each of the branch pipes 3 and 4 is a valve 10 in a casing 11, the casings having extensions 12 containing diaphragms 13 over the ends, and to these ends are attached caps 14 which secure the diaphragms in place. The stems of the valves 20 project into the extensions 12 and have heads 15 which are pressed against the diaphragms by spring elements 16, encircling the valve stems and engaging the heads 15 at one end and the inside of the extensions 12 with the other. The 25 springs 16 tend to close the valves, but when sufficient pressure acts on the diaphragms 13 the valves will open, and then water is admitted to both of the chambers 5 and 6. 30

At 17 is indicated a branch pipe which leads from the delivery conduit 8 to the valve casings 11 and is connected to the caps 14 so that pressure can be exerted on the diaphragms 13. This pipe 17 contains a valve element 18 between the two valve casings 11, said valve being shown as 35 a poppet valve although any suitable type may be used. This valve is normally closed by the weight of the magnetic plunger 20 of the solenoid 21, its stem 19 protruding from the pipe 17 and being affixed to said plunger. This solenoid is 40 united by conductors 22 to the electrical power circuit 23 which may furnish current to other parts of the apparatus, such as the motor for the pump 42 in the line of the conduit 8. In the line of one of the conductors 22 is a fixed contact 24 and a movable contact 25. The latter is connected by a link 26 to the movable end of an expandable casing 27. The opposite end of this casing is fixed and is connected by a piece of tubing 28 to a bulb 29 which is mounted in the 50 conduit 8 and is subject to the temperature of the chilled water therein. The tube 28 and bulb 29 together with the casing 27 are filled with an expandable fluid, and when this fluid contracts, due to the chilled water falling to a certain tem- 55

perature, the contacts 24 and 25 will be separated. At full load when the temperature of the chilled water is not so low as at part load, and when the apparatus is not operating, these contacts engage 5 each other, because the circuit to the solenoid 21 is then closed and the latter is energized.

The contents of the conduit 8 are impelled by the pump 42 to a cooling coil 43 in which the chilled water absorbs heat, and which is connected to the return pipe 2. The conduit 8 may contain therein at any suitable point, a check valve 44, this check valve being preferably located between the pipe 17 and coil 43. In the end of the pipe 17, beyond the two valves 10, is a hand operated valve 30 which may be permanently open slightly to give a constant leakoff, and through which the contents of this pipe may be discharged. The pipe 2 may also contain a hand control valve 45.

20 In operation, with the valve 45 open, the chilled water withdrawn from the chambers 5 and 6 through the conduit 8 and impelled to the cooling coil 43 by the pump 42 will be under some pressure. This pressure will be transmitted 25 to the pipe 17, and the water therein will act upon the diaphragms of the controlling valve means 10 and force these valves to open position to admit fluid to both the chambers 5 and 6. Both of the valves 10 will remain open so long 30 as the valve 18 is open. But if this valve 18 is closed, the adjacent valve 10 for the chamber 5 will be forced to close, leaving the other valve open and the chamber 6 alone in operation. Therefore, so long as the system operates at full 35 capacity, water will be chilled in both compartments 5 and 6; but in the event that the pump 42 is shut down to stop the system, or if this pump fails so that no more chilled water is impelled through the conduit 8, the necessary pressure 40 will no longer be exerted on the diaphragms 13. Both the valves 10 will therefore close and the water from the coil 43 will not drain back into the evaporator and flood it.

Likewise when the load drops, and the water 45 does not absorb so much heat in the coils 43, but comes back cooler to the evaporator 1, the temperature of the water in the pipe 8 falls and causes a contraction of the fluid in the casting 27, tube 28 and bulb 29. Then the circuit will 50 be open to the solenoid 21. The plunger 20 now can drop and the plunger 20 can move the valve 18 to closed position. The branch 3 will then be closed, but the branch 4 will remain open and the chamber 6 will continue to work.

55 Hence, the system is protected against flooding of the evaporator in case the chilled water pump fails, and the system is automatically regulated for part-load conditions by cutting out the chamber 5. This also tends to prevent freezing 60 of the evaporator by cutting out one chamber when the chilled water gets too cold. The cost of the system is low and the friction of the water in the pipes 3 and 4 is balanced by the use of similar branch pipes, similar valves and similar 65 headers 7.

The construction shown in Figure 2 operates in the same manner, except that the branch inlet member 3 alone has a diaphragm-actuated valve 10. Figure 2 is a top plan view partly in 70 section. In the branch inlet member 4 there is a disc 31 having a pressure-reducing opening or throttling orifice 32, this disc being held in place by flanged coupling members 33 on the adjacent ends of the pipe sections making up the 75 branch 4. The opening 32 is so designed that

when the branch 3 is open, the same amount of water will flow into the chamber 6 as into the chamber 5. In the event of the load dropping, the solenoid 21 allows the valve 18 to be closed and enables the valve 10 in the branch 3 to close, so as to prevent any more water from entering the chamber 5. This chamber is thus cut out at part load in the same way as described in regard to Figure 1.

To prevent draining into the evaporator and flooding the latter when the pump 42 is stopped or fails, a second valve 10a is placed in the line of the inlet member or main supply pipe 2 in advance of the branches 3 and 4. This valve is in all respects like the valve 10 in the branch 3 and is opened by pressure on the diaphragm 13. The cap 14a over the diaphragm 13 of the valve 10a in the inlet member or pipe 2 is also joined by way of a pipe 38 to the pipe 17.

Therefore, when the system is shut down, or if an accident happens to the pump 42, the valve means 10a in the pipe 2 closes and returning water is cut off entirely from the branches 3 and 4. The closing of valve 10a takes place because there will be no more pressure in the pipe 17 when the pump 42 stops. With valve 18 as shown in Figure 2, the valve 10 will then also close; but if the system is already operating at part load, and the valve 18 has cut off the valve 10, the valve 10a alone closes, cap 14 of valve 10 draining by way of valve 30.

To supply water to the pipe 2 to make up for loss, and thus replenish the system, a pipe 40 is connected to the evaporator, communicating therewith, for example, through the bottom of the chamber 6. The pipe 40 contains a rotary valve 35 with an outside arm connected by a link 36, slidably mounted in the wall of the evaporator, to a float-bearing lever 37 in the chamber 6. This lever is a bell crank mounted to move up and down in this chamber.

As long as the return water is plentiful the valve in the pipe 40 will be shut or nearly so, but if the system begins to run short of water the level of the liquid in the chambers 5 and 6 on the bottom will fall, so that the float lever 37 sinks and opens the valve 35 to a greater extent, and admits more make-up water into the chamber 6. On the other hand, a high level of water in the evaporator will keep the valve 35 closed. The amount of the make-up water is therefore determined automatically and is admitted in greater or less degree as conditions demand. The vapor liquefied in the condenser is returned to the evaporator in the usual manner, but the pipe 40 is needed in practice to make up any other losses that may occur.

The system in Figure 2 thus answers all the purposes of the system shown in Figure 1, besides automatically governing the admission of make-up water. The action of the valves is smooth and continuous, and the admission of make-up water is very uniform and regular.

The evacuating devices mentioned above for removing vapor from the chambers 5 and 6 will preferably have the form of centrifugal compressors, which have lately proved very successful for this purpose, and when the chamber 5 is cut out by the valve 18, the evacuating means for that chamber is rendered ineffective in any feasible manner. When the entire apparatus is stopped, the evacuating means for the remaining chamber or chambers is likewise put out of action. Steam jet evacuators may also be employed.

We claim:

1. In a refrigerating system, an evaporator for receiving and chilling a refrigerant, a pump for removing chilled refrigerant from the evaporator and for circulating same through the system, and pressure-responsive means actuated by the refrigerant discharge by the pump and acting to control the admission of refrigerant to the evaporator, said means being actuated independently 10 of the pressure of the refrigerant which it controls.
2. Refrigerating apparatus comprising an evaporator having chambers, a refrigerant inlet member for each chamber, a discharge conduit 15 connected to said chambers, valves in each inlet member, means dependent upon the refrigerant in the discharge conduit to control said valves, and additional means for separately controlling one of said valves.
3. Refrigerating apparatus comprising an evaporator having chambers, inlet members to admit refrigerant to the chambers, a discharge conduit connected to said chambers, a valve in one of said inlet members, a valve for all said 25 inlet members, means dependent upon the refrigerant in the discharge conduit to actuate said valves, and additional means for separately controlling one of said valves.
4. Refrigerating apparatus comprising an evaporator to receive and cool a refrigerant and then discharge same, inlet members to admit refrigerant to the evaporator, means dependent upon the pressure of the discharged refrigerant for separately determining the rate of flow of 30 refrigerant through each of said members, and additional means influenced by the discharged refrigerant for separately controlling one of said members.
5. Refrigerating apparatus comprising an evaporator for a refrigerant with chambers each having an inlet member for the refrigerant, a discharge conduit connected to the chambers, a valve in each of said members, means dependent upon the pressure of the discharged refrigerant 35 to actuate said valves, and additional means controlled by the temperature of the discharged refrigerant for independently controlling one of said valves.
6. Refrigerating apparatus comprising an evaporator having chambers, inlet members to admit refrigerant to the chambers, a valve for one of said inlet members, a valve for all of said members, a discharge conduit connected to said chambers, means dependent upon the pressure 50 of the discharged refrigerant to actuate said valves, and additional means for separately controlling one of said valves.
7. Refrigerating apparatus comprising an evaporator having chambers to receive a refrigerant, inlet members to admit refrigerant to the
- chambers, a discharge conduit connected to the chambers, means dependent upon the discharged refrigerant to control said inlet members, and additional means dependent upon the temperature of the discharged refrigerant for separately controlling one of said members. 5
8. Refrigerating apparatus comprising an evaporator having chambers, inlet members to admit refrigerant to the chambers, a discharge conduit for the chambers, a valve for the inlet member of one of said chambers, a second valve common to all said members, means dependent upon the discharged refrigerant to control all 10 said valves, and means dependent upon the temperature of the discharged refrigerant to control 15 separately the first of said valves.
9. Refrigerating apparatus comprising an evaporator having chambers to receive a refrigerant, inlet members to admit refrigerant to the chambers, refrigerant discharge means including, a conduit connected to the chambers, means dependent upon the pressure of the discharged refrigerant to control said inlet members, and means dependent upon the temperature 20 of the discharged refrigerant to separately control one of said members. 25
10. Refrigerating apparatus comprising an evaporator having chambers, inlet members to admit refrigerant to the chambers, a discharge conduit connected to the chambers, a valve for one of said inlet members, a valve common to all of said inlet members, means dependent upon the pressure of the discharged refrigerant to control said common valve, and additional means dependent upon the temperature of the discharged refrigerant to control separately the 30 first of said valves.
11. The combination with an evaporator having inlet and outlet members for refrigerant, of means for controlling the inlet members comprising pressure-actuated valves therein, means for supplying pressure medium to actuate the valves, control means in the supply means arranged to isolate some of said valves from the pressure medium without interrupting actuation 40 of the remaining valves, and electrically controlled means for actuating said control means and for effecting said isolation in accordance with the temperature of the refrigerant leaving said evaporator. 45
12. Refrigerating apparatus comprising an evaporator having chambers, a supply pipe having branches leading to each of said chambers, a valve in one of said branches, a valve in said pipe in advance of said branches, a conduit for enabling pressure to be exerted to actuate said valves, and a shut-off valve for one of said valves. 55
